(57) **CLAIM**

The ornamental design for a confectionery as shown and
described.

DESCRIPTION

The file of this patent contains at least one drawing/photograph
executed in color. Copies of this patent with color
drawing(s)/photograph(s) will be provided by the Office
upon request and payment of the necessary fee.

FIG. 1 is a front, top and right perspective view of a first
embodiment of a confectionery showing our new design;
FIG. 2 is a front, bottom and right perspective view thereof;
FIG. 3 is a front and left side perspective view thereof;
FIG. 4 is a rear elevation view thereof;
FIG. 5 is a front elevation view thereof;
FIG. 6 is a top plan view thereof;
FIG. 7 is a bottom plan view thereof;
FIG. 8 is a front, top and right perspective view of a second
embodiment of a confectionery showing the claimed design;

(Continued)

FIG. 9 is a front, bottom and right side perspective view thereof;
 FIG. 10 is a front and left side perspective view thereof;
 FIG. 11 is a rear elevation view thereof;
 FIG. 12 is a front elevation view thereof;
 FIG. 13 is a top plan view thereof; and,
 FIG. 14 is a bottom plan view thereof.
